LOCKING HANDLE FOR AUTOMOBILE DOORS

Filed Jan. 21, 1928.

Patented Feb. 26, 1929.

1,703,338

UNITED STATES PATENT OFFICE.

WILLIAM C. DEVEREAUX, OF DETROIT, MICHIGAN.

LOCKING HANDLE FOR AUTOMOBILE DOORS.

Application filed January 21, 1928. Serial No. 248,382.

This invention relates to door handles and particularly to locking handles for vehicle doors.

An object of the invention is the arrangement of a rotative, latch-controlling, vehicle door handle whereby it may be readily inserted into position for use when occupying a certain rotative position, and as readily removed therefrom when returned to the same rotative position in an unlocked condition, and to associate with said handle a common means for locking said handle against rotation and against removal from the door when in the specified position.

Another object is to extend the shank of a vehicle door handle through an aperture formed in a suitable member, and to provide upon said shank a projection, normally registrable by rotation with a restricted portion of said aperture to permit removal of the handle and shank, and actuatable to an increasingly projected position to prevent such removal, a portion of said projection being thereby engageable in the restriction of said aperture to prevent rotation of said handle.

A further object is to extend the shank of a vehicle door handle through an escutcheon member exteriorly attached to a door, and to dispose within said escutcheon member a spring exerting an inward thrust upon said shank to maintain the shank in operative position within the hub of the latch-bolt and also maintain firm contact between said escutcheon member and a finishing sleeve surrounding the shank between the handle and escutcheon member.

These and various other objects the invention attains by the construction hereinafter described and illustrated in the accompanying drawing, wherein:

Figure 1 is an axial horizontal sectional view of the herein disclosed handle installed upon a vehicle door, a portion of the outer sheathing of the door only being shown.

Figure 2 is a substantially similar view in which, however, the handle and its shank are locked against rotation and against removal from the door.

Figure 3 is a view in end elevation of said handle showing a fragmentary outside portion of the door which carries the handle.

Figure 4 is a cross-sectional view taken upon the line 4—4 of Figure 1, disclosing the aperture in the door through which the shank of the handle passes.

Figure 5 is a cross-sectional view taken

upon the line 5—5 of Figure 1 showing a provision for rigidly connecting the tubular outer portion of said shank to the inner stem portion of the same, and

Figure 6 is a perspective view of that portion of the door which is apertured to admit the shank of the handle, and showing a member carried by said shank actuatable to lock the shank in said aperture.

In these views the reference character 1 designates a handle mounted fast upon a shank 2, 3 for actuating a door latch mechanism (not shown). The outer member 2 of said shank is tubular and is connected to the handle in any suitable manner as by forming upon said member a terminal annular flange 4, which is welded or otherwise secured to the handle. The inner portion 3 of said shank has the nature of a stem of rectangular cross section which may be reduced at its inner end, as indicated at 5, to engage said latch mechanism and which has its outer end rigidly secured to the member 2 as, for example, by forming said stem with a terminal head 6, which is pinned or riveted within the inner end of the tubular member, as indicated at 7.

The member 2 passes through a slot 8 herein shown as substantially of a key-hole shape 85 jointly formed in the sheet metal outer sheathing 9 of a vehicle door and in a relatively thick sheet metal plate 10, welded or otherwise suitably rigidly attached to the interior face of said sheathing. The restricted portion of said slot is designated 8a.

The head 6 is diametrically slotted to slidably receive a bolt 11 adapted for actuation in its sliding travel upon turning movement of a cylinder lock 12 housed rotatively within the member 2 and eccentrically provided upon its inner end with a pin 13, which freely enters a groove 14 extending in the bolt 11 transversely of its sliding travel. The lock 12 is rotatively actuatable through some suitable control member, as an ordinary key 15.

The bolt 11 is disposed just within the sheathing 9 and partially occupies that portion of the slot 8 which is formed in the plate 10, the member 2 being formed with an opening 16 through which said bolt projects. The bolt 11 has at its outer end a tongue 17 so reduced in thickness and so offset toward the inner face of said bolt as to lie clear of the slot 8. When said bolt is retracted, as is illustrated in Figures 1 and 6, said tongue is

registerable with the restricted portion 8^a of the slot 8 in one rotative position of the shank 2, 3, thus providing for removal of the shank and its handle from the door when the escutcheon 18 is also free from the door. Also when said bolt is thus retracted, the shank is free to rotate in the opening 8 for actuation of the controlled latch mechanism (not shown). When, however, the cylinder lock 12 is turned (as by use of the key 15) to project the bolt 11 to the position shown in Figure 2, the body of said bolt engages in the restriction 8^a of the slot 8, locking said shank against rotation, and the tongue 17 of said bolt 11 overlaps the plate 10 to prevent outward withdrawal of the shank from the door, as long as the lock 12 remains in such locked position.

To impart a finished appearance to the installation an escutcheon plate 18, which may be a sheet metal stamping, is exteriorly secured by screws 19 to the sheathing member 9, and a sleeve 20 formed preferably of thin sheet metal encloses the tubular member 2 between the handle and said escutcheon. Normally the escutcheon 18 additionally serves to prevent any withdrawal of the shank 2, 3 from the door, there being a ring 21 upon said shank within said escutcheon and a spring 22 coiled about the shank within the escutcheon between an embossed central portion 18^a thereof and said spring. The ring 21 may be adapted in any suitable manner to transmit the inward thrust of the spring 22 to the shank. As shown, a thimble 23 which embraces the inner end portion of the member 2 provides a seat for the ring 21, said thimble having its inner end flanged inwardly as indicated at 23^a, and the stem 4 being slightly upset, as indicated at 24, to hold the flange 23^a against the head 6 of said stem. Thus the spring 22 urges the shank 2, 3 inwardly to constantly maintain firm contact between the finishing sleeve 20 and the escutcheon 18, tending to prevent rattle and automatically maintaining substantially the same exterior appearance on all the handles despite slight differences in widths of doors or spacing of the controlled latch mechanisms.

In the use of the described construction the handle 1 and the shank 2, 3 form a unit which is rotatable in the door to control a latch mechanism (not shown). Normally the bolt 11 is fully retracted and consequently is no hindrance to rotative actuation of the handle and shank. If it be desired to remove the handle and shank for effecting repairs or for any other purpose, this may be readily accomplished when the bolt 11 is retracted by withdrawing the screws 19 holding the escutcheon in place and then registering the tongue 17 of the bolt with the restriction 8^a of the slot 8.

65 In locking the handle 1 against use it is

also desirable to prevent any removal of said handle from the door. The bolt 11 when projected through rotative actuation of the cylinder lock 12 serves to accomplish both of these results, the tongue 17 of said bolt interiorly overlapping the plate 10 to prevent removal of the shank and handle and the body of said bolt engaging in the restriction 8^a to hold the shank and handle against rotation.

75 It is to be noted that the described construction accomplishes its purposes in an exceedingly simple manner and is comparatively inexpensive since its parts are primarily sheet metal such as may be economically produced in quantities by stamping operations.

80 While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

90 What I claim is:

1. In a latch handle mechanism, the combination with a handle, a shank carrying said handle, and a closure, of a member carried by said closure having an aperture receiving said shank and formed with a restriction at one side of the shank, a bolt carried by and slideable transversely of the shank and having an outer end portion registering with said restriction in the retracted position of said bolt 95 and interiorly overlapping said apertured member in its projected position to prevent withdrawal of the shank and handle from the closure, and means carried by the shank exteriorly of the closure for actuating said bolt. 100

105 2. In a latch handle mechanism, the combination with a normally rotative handle, a shank carrying said handle, and a closure, of a member carried by said closure having an aperture receiving said shank, and formed with a restriction at one side of the shank, a normally retracted bolt transversely slideable in said shank disposed partially within said aperture and having a tongue at the inner side of the apertured member, registerable in the 110 retracted position of the bolt with said restriction, whereby the shank and its handle are removable from the closure, said bolt being proportioned to enter said restriction, when projected, to lock said shank from rotation, and the tongue of the bolt when the latter is projected being adapted to overlap the inner face of the apertured plate to prevent withdrawal of the shank from the closure, and means carried by the shank exteriorly of the closure for actuating said bolt. 115

120 3. In a latch handle mechanism, the combination with a handle, a shank carrying said handle, and a closure, of a member carried by said closure having an aperture accommodat-

ing said shank, and formed with a restriction at one side of the shank, a bolt carried by the shank having a tongue registerable in one position of said bolt and in one position of rotation of said shank with said restriction to permit withdrawal of the shank and handle from the closure, said bolt being movable to engage in said restriction and to project its tongue beyond said restriction, to prevent withdrawal of the shank and means carried by said shank exteriorly of said closure for actuating said bolt independently of rotation of the shank.

4. In a latch handle mechanism, the combination with a latch handle, a shank carrying said handle, and a closure, of a member secured to said closure apertured to normally rotatively receive said shank and formed with a restriction at one side of the shank, a bolt carried by said shank movable relative to the shank to engage in the restriction of said aperture to lock the shank from rotation, and having a portion normally registerable with said restriction and adapted to overlap the inner face of said apertured member when the bolt is entered in said restriction, said bolt being transversely grooved, a cylinder lock rotatable in the outer portion of said shank, and a pin eccentrically carried by the inner end of said cylinder lock and engaging in said groove of the bolt to actuate the bolt from said lock.

5. In a latch handle mechanism, the combination with a closure and its latch handle, of a shank comprising a tubular outer member

carrying said handle and a stem secured at its outer end within said tubular member, a member carried by said closure formed with an aperture in which the tubular member of the shank is normally rotatable, said aperture having a restriction at one side of the tubular member, a bolt carried by said tubular member adjacent to said stem and having a tongue normally registerable with said restriction to permit removal of the shank and handle from the door, said bolt being movable relative to the shank into the restriction of said aperture to lock the shank from rotation and to project said tongue beyond said restriction and thereby to prevent withdrawal of the shank from the door, and means within the tubular portion of the handle for retracting and projecting said bolt.

6. In a latch handle mechanism, the combination with a latch handle and a shank carrying said handle, of a closure in which said handle is rotatable a member interiorly secured to said closure, said member and closure being jointly formed with a slot of substantially key-hole shape, a bolt carried by the shank and movable relative thereto to engage in the restriction of said slot to lock the shank from rotation, said bolt having a tongue projecting beyond said slot in the locking position of the bolt to prevent removal of the shank and handle, and means carried by the outer portion of said shank for actuating said bolt.

In witness whereof I hereunto set my hand.

WILLIAM C. DEVEREAUX.
